UNITED STATES PATENT OFFICE.

CARL MEYER, OF ZURICH, SWITZERLAND.

CORD GUIDE FOR ROLLING TOYS RUNNING ON CORDS.

Application filed July 23, 1925, Serial No. 45,558, and in Germany July 26, 1924.

This invention relates to a cord guide for a toy running—by means of a roller—on a cord. This cord guide has for its object, on one hand, to maintain the cord on the roller and, on the other hand, to effectively dampen the disturbing swinging of the toy, so that a smooth flight is obtained.

With the present invention in view it is possible for the toy to effect all sorts of curves, loops and the like, as the cord if thrown off will always slip back again into contact with the roller, as it cannot jump out of the guide.

This is attained in such manner that, between roller and toy, a space is formed, closed on four sides, which does not allow the cord to slide off or to slip out, but, on the contrary, always forces it to slide again self-dependently into the right position.

The invention is shown, in several forms of construction, in the accompanying drawings, in which:

Fig. 1 is a front elevation of the cord guide.

Fig. 2 is a side view of the same.

Fig. 3 is a front elevation of a modified form of the cord guide.

Fig. 4 is a side view of Fig. 3.

Fig. 5 a front elevation of another modified form of the cord guide.

Fig. 6 is a side view of Fig. 5.

Referring particularly to Figs. 1 and 2, the toy for which the cord guide is intended, and which may be, for instance, a miniature aeroplane, (not shown), is suspended from, or otherwise attached, to a plate *a*, which is also the support of the cord guide. On this plate two bows *b*, *b*, of annular form are rigidly mounted. At their upper parts these bows are formed with tongues *b*¹, *b*¹, which are bent horizontally towards each other, and, at their ends are bent upwardly to produce ears *i*, *i*, pierced for the reception of a connecting rivet *i*¹.

The roller *c*, which has its shaft *d* mounted in bearings *e*, formed in standards *e*¹, attached to the plate, is mounted with its ends passing through the openings in the bows *b*, *b*.

The standards *e*, *e*¹, are bent horizontally

at their upper parts and are then bent upwardly to form ears *k*, *k*, which embrace the ears *i*, *i*, of the bows *b*. The bows and bearing standards are fastened together by means of the rivet *i*¹, *i*¹, passing through the ears *i*, *i*, *k*, *k*.

The described construction and arrangement forms a cage closed on four sides, leaving a space through which is passed the cord *f*, on which the roller *c*, travels. By reason of this enclosure or caging, the cord is prevented from jumping out of position while the toy is executing various movements.

In the modified construction shown in Figs. 3 and 4, the standards *e*¹, for the roller shaft, and the bows *b*², *b*², are disconnected at their upper ends, but, as shown in Figs. 1 and 2, the ends of the roller pass through and are embraced by the bows thus providing a cage and guide through which the cord passes, below the roller, and is prevented from jumping out of position.

In the modified construction shown in Figs. 5 and 6, the bows are in the form of caps *b*³, *b*³, which cover the ends of the roller and are fastened to the plate *a*. These caps or covers may be connected together at their upper ends by forming ears thereon and passing a rivet therethrough.

Said caps are pierced centrally for the passage of the roller shaft which has its bearings in said caps instead of in separate standards.

It is to be observed that in each of the forms of the cord guide described and shown, the roller, preferably a pulley, having a double conical or hour-glass shape, is provided with a shield or cage, constituted of the bows, the supporting plate and the roller itself which prevents the cord, passing under the roller and through the caged space, from being thrown off the pulley, or conversely prevents the toy from being thrown off the cord.

The invention therefore, resides broadly in the provision of means, to wit: the bows or guards, for enclosing between four limiting planes or walls, a space through which the cord passes, the vertical limiting planes or walls being located between the ends

of the roller and embracing the same below the axis of the roller..

I claim:-

1. A cord guide for rolling toys, comprising, in combination, a supporting plate, a roller, bearings for the reception of the axle of the roller, mounted on the supporting plate, two bows located between the ends of the roller, for guiding the cord, and a cord passed between the lower part of the roller, the supporting plate and bows, said bows being partially situated below, and em-

bracing the lower part of the roller, and forming a closure to prevent the displacement of the cords at the ends of the roller.

15

2. A cord guide for rolling toys, comprising, in combination, a supporting plate, a roller, cap like coverings for the ends of the roller, mounted on the supporting plate, and forming both bearings for the roller shaft, and bows to prevent dislodgment of the cord at the ends of the roller.

20

In testimony whereof I affix my signature.
CARL MEYER.
